UNITED STATES PATENT OFFICE.

ROBERT MIEHLE, OF CHICAGO, ILLINOIS.

PRINTING-PRESS.

No. 909,199.

Specification of Letters Patent.

Patented Jan. 12, 1909.

Application filed March 7, 1904. Serial No. 196,690.

To all whom it may concern:

Be it known that I, ROBERT MIEHLE, a citizen of the United States, residing at Chicago, in the county of Cook and State of Illinois, have invented certain new and useful improvements in Printing-Presses, of which the following is a full, clear, and exact specification.

My invention relates to that class of flat bed printing presses, usually combined with a sheet delivery mechanism, in which the ink fountain and apparatus is arranged at one extremity of the stroke of the bed just under the piling table or other sheet receiving surface. This relative location of the piling table and ink fountain is found very objectionable in that the ink fountain and apparatus is not readily accessible during the operation of the press and even at other times is awkward of management and requires the table to be moved; and furthermore, which is probably a more serious objection, it very materially curtails the range of vertical movement of the piling table rendering it incapable of being started at a high elevation and lowered close to the floor while receiving sheets.

My invention is designed to overcome these defects, and therefore has for one of its objects to provide a passage-way for the attendant or workmen between the ink fountain or apparatus and the piling table or other sheet receiving surface.

A further object of my invention is to provide for a wide range of vertical movement of the piling table or sheet receiving surface.

With these ends in view, my invention consists in certain features of novelty in the construction, combination and arrangement of parts by which the said objects and certain other objects hereinafter appearing are attained, all as fully described with reference to the accompanying drawings and more particularly pointed out in the claims.

In the said drawings,—Figure 1 is a side elevation of my improved printing press. Fig. 2 is an enlarged detail view hereinafter described. Fig. 3 is a side elevation of the press looking from the opposite side to that presented in Fig. 1, and Fig. 4 is a plan view thereof.

The printing press proper is of a well known type of flat bed press comprising among the usual features or mechanism an ink fountain or apparatus A, arranged at one end of the stroke of the bed and supported in the usual

manner upon the main frame 1 at the opposite end of which is journaled the usual impression cylinder B. This ink fountain or apparatus in presses of this character has heretofore been mounted under the sheet piling table, downwardly towards which the sheet conveying tapes 2 conduct the sheet to a position over the sheet delivery which may be of the well known fly finger type or reciprocating carrier, but according to my present invention the conveyer tapes 2 are supported at an elevated position by an upwardly extending frame 3, high above the ink fountain A, and the piling table C is set off from the ink fountain A at a considerable distance therefrom so as to form a passage-way D between the table or other sheet receiving surface and such fountain whereby the workmen or attendant may pass freely between the table and the fountain, and free access to the fountain and other parts of the inking apparatus may be had during the running of the press and at all other times.

The sheet piling table C or other sheet receiving surface is supported at a considerable elevation in a suitable frame 4, which also serves as a means for supporting the ways or tracks 5, 6 for the sheet carrier carriages 7, 8, at one end while the opposite ends of these ways 5, 6 are supported by extensions 9, 10 of the frame 3. The sheet delivery mechanism itself may be of the usual or any suitable form, but in this exemplification of the invention it is preferably of the double interchangeable form of reciprocating sheet carrier and fly finger delivery shown in my United States Patent No. 610,491 granted September 6th, 1898 to which reference may be had for an understanding of the construction and operation of any details of the delivery not herein described and illustrated. In this double form of delivery it will be seen that the tracks or ways 5, 6 are pivoted in the frame extensions 9, 10 on suitable studs or pivots 11, 12 respectively, so that when it is desired to cease using the reciprocating sheet carrier for delivering the sheets upon the piling table or sheet receiving surface C, these tracks or ways 5, 6 may be stood up out of the way where they remain in a slightly reclining position resting respectively against two bosses 13, 14 projecting inwardly from the extensions 9, 10 respectively, thus making room for the fly fingers 15 to oscillate back and forth on their rocker shaft 16 from a position extending

across the passage-way D to a position overlying the table C. It is, of course, understood that when the fly fingers are thus used the carriages 7, 8 are forced upwardly to the upper ends of the ways 5, 6, and the sticks 17, which are supported on said carriages by a cross-rod 18, are turned outwardly in a horizontal or substantially horizontal direction, as clearly illustrated in Fig. 8 of my aforesaid patent, to make room under the supporting rod 18 for the passage of the sheet and the fly fingers 15.

The carriages 7, 8 are given their necessary reciprocating travel on the ways 5, 6 by suitable operative connections extending across the passage-way D to the operating mechanism of the press proper, and these connections, as also the connections for operating the fly fingers to be presently described, instead of being carried across the passage-way D near the floor line, which would bring them in the way of the feet of the attendant, are preferably carried across at an elevation high above the ink fountain or mechanism. Each of the carriages has means of detachable connection with two links 19, 20 which are respectively connected with vibratory arms or levers 21, 22 secured to a rocker shaft 23, which is journaled in the frame extensions 9, 10, and one end of this shaft 23 is provided with a rocker arm 24 detachably clamped thereto, all as shown and described in my aforesaid patent. One end of this rocker arm 24 is pivoted to a substantially horizontal rod 25, which extends across the passage-way D and is pivotally connected with one end of a lever 26 fulcrumed on one of the frames 3 and having its other end connected by a downwardly extending rod 27 to a revolving crank 28 secured to the shaft 29 which rotates the usual fly operating cam 30, the connection between the rod 27 and the wrist pin 31 of crank 28 being of a detachable character so that the rod 27 may be thrown out of action when it is desired to use the fly delivery, but so long as the rod is connected to the crank it will be seen the necessary reciprocating travel will be imparted to the carriages 7, 8, the sticks of which project rearwardly across the passage-way D and between the tapes 2 so as to support the sheet as it is drawn forward from the tapes 2 by the usual grippers which are supported on the carriages 7, 8, as fully described and shown in my aforesaid patent.

The rocker shaft 16 which carries and oscillates the fly fingers 15 is operated as usual by the cam 30, but in my present invention this shaft 16 is arranged at the side of the passage-way D opposite that on which the inking apparatus A is situated, and it is connected to the usual pinion or toothed segment 32 by means of a transverse shaft 33 journaled in the frames 3 and a second pinion

or toothed segment 34 (see Fig. 3) mounted on the opposite end of the shaft 33 and engaging with a rack-bar 35 arranged above it on the end of a connecting rod 36 which extends horizontally across the passage D to another pinion or toothed segment 37 secured to the rocker shaft 16 and engaging a rack-bar 38 secured to or formed on the outer end of rod 36, the two rack-bars 35, 38 being arranged to slide in suitable keepers 39, 40 pivoted around the centers of shafts 16, 33, respectively, similar to the keeper 23 shown and described in my aforesaid patent. Thus it will be seen that when the shaft 33 is oscillated similar oscillation will be imparted to the shaft 16 and consequently the fly fingers 15 will be moved back and forth across the passage-way D, resting below the tapes 2 until the sheet arrives at the limit of its travel on said tapes over the passage-way, and then rising between the tapes in the usual way for flying the sheet and inverting it upon the piling table.

The pinion or segment 32 on the shaft 33, which latter in my former patent aforesaid served as a means of supporting and oscillating the fly fingers, derives oscillation or back and forth rotation in the usual way from cam 30, that is to say, by a lever 41 pivoted to frame 1 and carrying an anti-friction roller 42 adapted to be held in contact with the periphery of cam 30 by a spring 43 on a connecting rod 44 pivoted at one end to lever 41 and having its other end provided with the usual rack-bar 45 sliding in usual keeper 46 and engaging pinion 32. When the reciprocating carrier is to be used the lever 41 is held out of action by any suitable stop 47.

48 is the usual spring actuated rod connected by a crank 49 to fly finger shaft 16 for assisting in throwing the fly towards the table, as well understood, the rod being supported in this instance on the side of frame 4 in an upright position in suitable guides 50, 51.

By thus locating the piling table C at a distance from the inking apparatus I not only provide a passage-way between it and the inking apparatus, but I very materially increase the receiving capacity of the table and am enabled to make the table vertically adjustable throughout a wide range of movement above the floor. To this end, therefore, the table is supported at both sides by vertical screws 52, 53 journaled in the frame 4 and having threaded connection with the table so that when the screws are rotated the table will descend or ascend according to the direction of rotation. The upper ends of these screws 52, 53 are connected together by a counter shaft 54 journaled across the inner side of the frame 4 and having at its ends two sprocket wheels 55, 56, which are connected respectively by chains 57, 58 with sprocket wheels 59, 60 on stud shafts 61, 62

110

115

120

125

130

journaled in suitable brackets 63, 64 on top of frame 4, and having miter gear connection 65, 66 respectively with the upper ends of screws 52, 53 so that the screws will be driven in unison when the shaft 54 is rotated. The shaft 54 is thus rotated automatically by any suitable connection with the sheet delivery mechanism. This connection, for the reciprocating form of delivery comprises a long pawl 67 pivoted to rocker arm 24 and arranged to engage a ratchet wheel 68 secured to shaft 54, each time the rocker arm makes a backward movement, thus rotating the shaft 54 a sufficient distance to lower the table C approximately a distance equal to the thickness of a single sheet of paper, or equal to the thickness of a plurality of sheets if a plurality be delivered upon the table at one time, the extent of the effective action of the pawl 67 being regulated by a deflecting cam 69, adjustably secured at 70 to the side of frame 4 and serving to hold the point of the pawl out of engagement with the ratchet wheel throughout a greater or less extent of its stroke. The means for rotating the ratchet by the action of the fly fingers is shown in Fig. 2 and consists of a pawl 71 pivoted detachably to a short crank arm 72 secured on the end of fly finger shaft 16 and capable of being thrown back out of the way or removed when the reciprocating delivery is to be used.

The table may be raised or lowered rapidly by hand when desired through the agency of a crank 73 secured to shaft 54. By thus connecting the vertical screws of the table mechanism to a countershaft located at any point out of the range of both the table itself and the fly, it will be seen that I am enabled to impart movement to the table automatically without interfering in any way with the movement of the delivery or curtailing the range of movement of the table, or interfering with the introduction of a truck under the table for allowing the latter to be loaded directly onto it in case it should be desired to do so.

The improvements in the automatically operating piling table shown and described herein but not claimed, constitute the subject matter of my co-pending application, Serial No. 283,376, filed October 19, 1905.

Having thus described my invention, what I claim as new therein and desire to secure by Letters Patent is:

55 1. In a printing press, the combination of a flat bed press proper comprising an inking apparatus arranged at one end of the bed and an elevated sheet receiving surface set off laterally from said inking apparatus to provide a horizontal passage way and floor space for workmen between them, and mechanism for delivering the sheet from the press proper to said sheet receiving surface across said passage-way at an overhead elevation.

65 2. In a printing press, the combination of

the press proper and an elevated sheet receiving surface set off from each other to provide a passage-way for workmen between them, means for delivering the sheet from the press proper to said receiving surface arranged at an overhead elevation and bridging said passage-way and means operatively connected with the press proper for moving said sheet delivery mechanism back and forth across said passage-way. 75

3. In a printing press, the combination of the press proper comprising an ink fountain, an elevated sheet receiving surface set off from the end of the press proper at a distance from said ink fountain to provide a vertical 80 passage way and floor space for workmen between said surface and fountain and a sheet delivery mechanism bridging said passage-way at an overhead elevation for delivering the sheets from the press proper upon said 85 receiving surface.

4. In a printing press, the combination of the press proper, and an elevated sheet receiving surface set off laterally from each other to provide a passage-way for workmen 90 between them, a sheet delivery mechanism movable at an overhead elevation for conducting the sheet from the press proper across said passage-way to said sheet receiving surface and operative connections between the mechanism of the press proper and said sheet delivery extending across said passage. 95

5. In a printing press, the combination of the press proper, and an elevated sheet receiving surface set off laterally from each other to provide a passage-way for workmen 100 between them, sheet conducting tapes extending across said passage-way from the press proper to said sheet receiving surface, 105 a sheet delivery situated at the outer ends of said tapes for taking the sheet therefrom and delivering it upon said sheet receiving surface, and mechanism extending across said 110 passage-way at the end thereof only for operatively connecting the sheet delivery with the mechanism of the press proper.

6. In a printing press, the combination of the press proper and an elevated sheet receiving surface set off laterally from each 115 other to provide a passage-way for workmen between them, a sheet delivery arranged at an overhead elevation for delivering the sheets from the press proper upon said surface, and an operating mechanism crossing 120 said passage-way at an overhead elevation and operatively connecting said sheet delivery with the operating mechanism of the press proper.

7. In a printing press, the combination of the press proper and an elevated sheet receiving surface set off from each other to provide a passage-way for workmen between them, a sheet delivery arranged at a high elevation for delivering the sheets from the 125 130

- press proper upon said surface, elevated rocker shafts on opposite sides of said passage-way, an operative connection between one of said shafts and said sheet delivery, an operative connection between the other of said shafts and the operating mechanism of the press proper and means connecting said shafts together across said passage-way.
8. In a printing press, the combination of the press proper and a sheet receiving surface set off from the press to provide a passage-way between them, rocker members arranged at both sides of said passage, means connecting said rocker members together across said passage, means connecting one of said members with the operating mechanism of the press and a sheet delivery operatively connected with the other of said members.
9. In a printing press, the combination of the press proper and a sheet receiving surface set off from the press to provide a passage-way between them, operating members arranged at both sides of said passage, means connecting said operating members together across said passage, means connecting one of said members with the operating mechanism of the press and a sheet delivery operatively connected with the other of said members.
10. In a printing press the combination of the press proper, a sheet receiving surface set off from the end of the press to provide a passageway for workmen extending transversely of the press at the end thereof, and means movable from the press to the said sheet receiving surface in an overhead position across said passageway for delivering the sheet to the said sheet receiving surface.
11. In a printing press the combination of the press proper, a sheet receiving surface set off from the end of the press and providing floor space and a head-high passageway between them, extending transversely of the press, means movable in an overhead position from the press to the sheet receiving surface, across said passage, and means operatively connecting the last said means with the mechanism of the press for causing it to deliver the sheet to said sheet receiving surface.
12. In a printing press the combination of the press proper, a sheet receiving surface set off from the end of the press to provide a head-high passageway between the end of the press and said surface, means extending across said passage-way from the press to the sheet receiving surface in an overhead position for conducting the sheet from the press to said sheet receiving surface, and means operatively connected with the press for actuating the last said means, said passage-
- way being entirely unobstructed from the floor space to a head-high elevation and from one side of the press bed to the other.
13. In a printing press the combination of the press proper, a sheet receiving surface set off laterally from the end of the press to provide a head-high passageway between said surface and the end of the press, a sheet delivery mechanism arranged contiguous to said surface at the side of said passage remote from the press, and movable from the press to the said surface at an overhead elevation for conducting the sheets from the press to said surface, and means connecting said sheet delivery with the mechanism of the press, across said passage.
14. In a printing press, the combination of a flat bed press proper comprising an inking apparatus arranged at one end of the bed and an elevated sheet receiving surface set off laterally from said inking apparatus to provide a horizontal passageway and floor space for workmen between them, sheet delivery mechanism operatively connected with the press proper for delivering the sheet to said sheet receiving surface across said passageway, arranged in an overhead position and having all its moving parts confined to an overhead line of movement throughout the width of said passage in such a way as to leave a permanently unobstructed passage for workmen contiguous to the end of the line of stroke of the bed of the press, whereby such workmen may have free access to the said inking apparatus.
15. In a printing press, the combination of a flat bed press proper, comprising an inking apparatus arranged at one end of the bed, an elevated sheet receiving surface set off laterally from said inking apparatus to provide a horizontal passageway, and floor space for workmen between them, sheet delivery mechanism for delivering the sheet to said sheet receiving surface across said passageway, arranged in an overhead position so as not to obstruct said passageway, and an operative connection extending permanently across the passageway for connecting the sheet-delivery mechanism with the press proper, said delivery mechanism and operative connection being so arranged and having their line of operation so confined as to leave unobstructed the passageway and floor space for workmen immediately contiguous to the end of the line of movement of the bed, whereby the workmen may have unmolested access to the inking apparatus.
